UNITED STATES PATENT OFFICE.

EDWARD LOUIS PEMBERTON, OF NEW YORK, N. Y., ASSIGNOR TO THE FROG SWITCH & MANUFACTURING COMPANY, OF CARLISLE, PENNSYLVANIA, A CORPORATION OF PENNSYLVANIA.

DIPPER TOOTH.

Application filed February 16, 1923. Serial No. 619,831.

To all whom it may concern:

Be it known that I, EDWARD L. PEMBERTON, a citizen of the United States, residing at New York city, in the county of New York and State of New York, have invented certain new and useful Improvements in Dipper Teeth, of which the following is a specification.

This invention relates to teeth for excavating dippers or shovels, or the like, an object of the invention being to provide a tooth having improved means for interlocking the point and base of the tooth, so as to resist or prevent relative movement thereof.

A further object of this invention is to provide an improved dipper or shovel tooth comprising a point and a base connected together, which tooth will be strong and durable for withstanding efficiently the shocks or strains to which it is subjected during use, and which at the same time will be relatively easy and inexpensive to manufacture.

A further object of this invention is to provide a dipper or shovel tooth comprising a base and a point connected together, the point and base having an improved lug construction for securely interlocking the point and base together.

A further object of this invention is to provide an improved shovel point adapted to be connected to the base member of the tooth, the point having inwardly extending side lugs between which the base fits.

Other objects of this invention will appear in the following description and in the appended claims, reference being had to the accompanying drawings forming a part of this specification, wherein like reference characters indicate corresponding parts in the several views, and wherein Fig. 1 is a longitudinal sectional elevation of a part of an excavating dipper or shovel and illustrating a tooth embodying this invention and connected thereto; Fig. 2 is a top plan view of a tooth; Fig. 3 is a perspective view of the point; Fig. 4 is a perspective view of the base of the tooth; Fig. 5 is a perspective view of a somewhat modified form of point; and Fig. 6 is a perspective view of a somewhat modified form of base of the tooth.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

In the construction illustrated in Figs. 1 to 4 inclusive, it will be seen that the present improved dipper or shovel tooth comprises a wedge-shaped point 9 bifurcated to provide a pair of rearwardly extending jaws or members 10 and 11 forming a wedge-shaped recess therebetween for receiving the nose of the base of the tooth. The jaw 11 is tapered rearwardly to a suitable distance and is preferably provided with a straight horizontal extension 12, the lower jaw in the present instance thus being preferably longer than the upper jaw. The jaws 10 and 11 are connected together in spaced relation by means of a central web 13.

The base 14 of the tooth is bifurcated to provide a lower jaw 16 and an upper jaw or shank 15 extending rearwardly thereof, the parts 15 and 16 thus forming a space therebetween, into which the bottom 41 of a suitable dipper or shovel 40 fits. The base of the tooth is also provided with a wedge-shaped nose 17, which is slotted centrally thereof to provide a recess 18, into which the wedge 13 is seated when the point and nose are assembled. The rear end of the upper jaw 10 is preferably beveled at 19 so as to extend in prolongation of the upper face of the shank 15, as shown in Fig. 1.

In the form of tooth illustrated in Figs. 1 to 4 inclusive, it will be seen that the extension 12 of the lower jaw 11 is of substantially the same width throughout, and has substantially the same width and length as the lower jaw 16 of the base 14. The extension 12 is provided with a pair of inwardly extending lugs 20 and 21, which are preferably cast integrally therewith and are preferably formed outwardly from the side edges of the member 12. The lugs 20 and 21 extend above the upper horizontal face

of the member 12 a distance substantially the same as the thickness of the jaw 16, and it will be seen that the lugs form a space or channel therebetween, into which the jaw 6 or member 16 of the base fits.

Thus it will be observed in this construction that the point 9 and the base 14 may be readily assembled by sliding the parts together, the space between the lugs 20 and 21 permitting the base to slide and fit snugly therebetween. When the point and base are assembled, these lugs project over the outer edges or faces of the jaw 16 and form a rigid interlocking means for resisting or preventing relative sidewise movement of the point and base when subjected to lateral strain or shock.

The point and base are in the present instance provided with a pair of aligned bolt holes 22 and 23 respectively, through which suitable bolts 24 extend for the purpose of fastening the parts together. It will be seen that the fastening bolts for the point and base are located rearwardly of the wedge-shaped nose 17, and since the lugs 20 and 21 are also located adjacent thereto, the latter positively serve to relieve the bolts 24 of any strain due to transverse shocks or strains. The relationship therefore of the fastening bolts 24 and the interlocking lugs 20 and 21, which are all positioned in close proximity, is important in preventing the tendency of the bolts to shear, and hence by virtue of this relationship the lugs 20 and 21 effectively reinforce the fastening bolts.

In the construction illustrated in Figs. 5 and 6, the point 25 is also bifurcated to provide a pair of rearwardly extending jaws 26 and 27 forming a wedge-shaped recess therebetween for receiving the nose of the base. The jaws are connected together by means of a central web 28, and the lower jaw is also provided with a rearward extension 27^a. In this instance, the upper jaw 26 is also beveled transversely at 26^a, and the extensions 27^a of the lower jaw has the side edges thereof tapered inwardly, as shown at 29. The base 30 in this form of construction is also bifurcated to provide a lower jaw 32 and an upper jaw or shank 31 of greater length, the members 31 and 32 thus being spaced apart to provide a seat for receiving the front edge of the dipper bottom 41. The rear portion of the lower jaw 32 of the base is also tapered at 33 to correspond in size to the tapered end 29 of the lower jaw of the point.

The rear end of the extension 27^a in the present instance is tapered or beveled transversely thereof at 34, and the rear end of the lower jaw 32 of the base is provided with a transverse tapered shoulder 35 cooperating with the tapered portion 34 when the point and base are assembled.

Forwardly of the tapered side edges 29 of

the extension 27^a are located a pair of inwardly or upwardly extending lugs 36 and 37. These lugs are preferably formed in substantially the same manner as the lugs 20 and 21 hereinbefore described, and when the point and base are assembled the lugs 36 and 37 project over the outside faces or edges of the jaw 32 forwardly of the rearwardly tapered portion 33 thereof.

The base 30 is provided with a tapered wedge-shaped nose 42, which extends into the wedge-shaped recess formed by the jaws 26 and 27 of the point, and this nose 42 is slotted to form a recess 28^a, into which the web 28 extends. When the point and base are assembled, the same are secured together by means of suitable fastening bolts extending through aligned bolt holes 38 and 39 of the point and base respectively.

It will be noted that the bolts 24 not only secure the point and base together, but also serve to secure the tooth to the bottom 41 of the dipper or shovel 40.

Heretofore it has frequently been the practice, in order to interlock the point and base of the tooth to provide one of the jaws of the point with a central lug, which fits into a recess in the base. Such a construction has in practice been found to have serious disadvantages because of the difficulty of machining accurately the lug and recess, so as to exactly fit without any relative movement of the point and base, and this construction has therefore been relatively expensive.

In the present instance however, the side lugs 20 and 21, or 36 and 37, may be readily cast on the side edges of the jaw, and since the jaw is formed anyway with a width to fit the juxtaposed part of the base of the tooth, the latter will snugly fit between the lugs, and hence the expense of machining lugs and recesses, as heretofore, is eliminated.

The importance of this will be immediately understood, since it is a well known fact that it is an extremely difficult operation to machine manganese steel, and due to the character of the work required of dipper teeth, they are uniformly constructed of manganese steel.

It is to be understood that by describing in detail herein any particular form, structure, or arrangement, it is not intended to limit the invention beyond the terms of the several claims or the requirements of the prior art.

Having thus explained the nature of my said invention and described a way of constructing and using the same, although without attempting to set forth all of the forms in which may be made, or all of the modes of its use, I claim:

1. A dipper tooth comprising a base and a point bifurcated to embrace said base, said

- base and point having one a pair of lugs at the sides thereof overlapping the outer side edges of the other.
2. A dipper tooth comprising a base and a point bifurcated to embrace said base, said base and point having one a pair of lugs formed outwardly from the plane of the side edges thereof and overlapping outer side faces of the other.
- 10 3. A dipper tooth point bifurcated to form a pair of jaws, one of said jaws having an inwardly extending lug formed outwardly from a side edge thereof.
4. A dipper tooth comprising a base having a tapered nose and a rearwardly extending member adapted to engage the dipper bottom, and a point having a lug overlapping a part of said member in rear of the nose and extending outside the plane of the side edge of said member.
5. A dipper tooth comprising a base having a tapered nose and a rearwardly extending member adapted to engage the dipper bottom, and a point having a pair of lugs overlapping and embracing therebetween said member, said lugs being spaced apart a distance as great as the greatest width of said member adjacent to the points of overlapping.
- 30 6. A dipper tooth comprising a base and a point bifurcated to embrace the base, and means for interlocking said base and point and comprising a pair of lugs extending outside the plane of the outer sides of said base and point.
7. A dipper tooth comprising a base and a point bifurcated to embrace the base, and means for interlocking said base and point and comprising a pair of lugs extending entirely outside the plane of the outer sides of said base and point, and means adjacent to said lugs for securing the point and base together.
- 45 8. A dipper tooth comprising a base and a point bifurcated to embrace said base, and means for interlocking said base and point and comprising a pair of lugs spaced apart a distance as great as the greatest width of said members adjacent to the lugs.
9. A dipper tooth comprising a point and a base having one a transverse tapered face and the other a tapered shoulder portion engaging said face, and means for interlocking said base and point and comprising a pair of lugs embracing the outer sides of one thereof.
10. A dipper tooth comprising a base and a point each bifurcated to form a pair of rearwardly extending jaws located in juxtaposition, and means for interlocking said jaws against relative movement and comprising a pair of lugs extending outside the plane of the side edges of said jaws.
11. A dipper tooth comprising a base and a point each bifurcated to form a pair of rearwardly extending jaws located in juxtaposition, said jaws having lugs engaging the same and embracing the side edges of one thereof, and a bolt extending through said jaws adjacent to said lugs.
12. A dipper tooth comprising a point bifurcated to form a pair of jaws, a base cooperating therewith, and means for interlocking said point and base and comprising a pair of lugs, one thereof overlapping a jaw and a part of the base and extending outside the plane of the side edges of the jaw and base at the point of overlapping.
13. A dipper tooth comprising a base member and a point member adapted to be joined together, and means for interlocking said members against relative movement and comprising a pair of lugs, each lug projecting outwardly from the edge of one of the members and overlapping a non-recessed portion of the other member.

Signed at 30 Church St., New York, N. Y., this 15th day of February, 1923.

EDWARD LOUIS PEMBERTON.
